UNITED STATES PATENT OFFICE

HARRY A. KAUFMANN, OF HIGHLAND PARK, MICHIGAN

RAZOR

Application filed September 20, 1928. Serial No. 307,102.

One of the primary objects of my invention is to provide economical and efficient means for rendering safe the use of what is commonly known as a straight edge razor. It is well known that the various types of safety razors which are commonly used are highly inefficient and expensive because of the necessity for repeatedly changing the blades thereof. I propose to construct a razor of the well known straight edge type which may be easily sharpened any number of times and which when sharpened will provide an efficient and painless shave.

Among the specific objects of my invention are the provision of a guard for the razor blade which will tend to prevent accidental cutting of the user and which may at the same time be adaptable to stropping of the razor in order to sharpen the same. It is also adaptable to ready use of either side of the blade of the razor. Another object is to provide simple means whereby the guard may be moved at a considerable distance from the razor in order to permit cleaning of the same or to permit shaving of parts of the face which would be inaccessible with the guard in place.

With the above and other objects in view, my invention consists in the arrangement, combination and construction of the various parts of my improved device as described in the specification, claimed in my claims and shown in the accompanying drawings, in which:

Fig. 1 is a side elevation of a razor having my invention applied thereto.

Fig. 2 is an enlarged view of the same with the attaching and controlling mechanism for the guard shown in section.

Fig. 3 is a sectional view taken on line 3—3 of Fig. 2.

I have shown a razor embodying a handle 5 and blade 6, the latter having a cutting edge 7.

The cutting edge 7 of the razor is adapted to be protected by a guard 8 which extends along the said edge and is provided with bent up ends 9 and 10. The end 9 extends into an opening in the extreme outer end of the blade 6, as indicated by the dotted lines 11 in Fig. 1, so as to be pivoted thereto.

The end 10 is rounded at its extremity and bent to a horizontal position, as indicated at 12. This rounded extremity is adapted to bear within a member 13 which is secured to the shank of the blade 6 by screws 14 and 15. The screw 15 also serves to secure in place a piece 16 which is provided along the outer face of the member 13.

Aligned openings are provided in the pieces 13 and 16 through which a setscrew 17 may extend. This screw is threaded into the opening in the member 16 but the opening in the member 13 clears the same as is indicated at 18 in Fig. 2.

The inserted end of the setscrew 17 extends to a point adjacent the rounded extremity 12 of the guard. In fact, the extremity is provided with a cut out slot 19 into which the inserted end of the setscrew extends, there being a slight clearance between the end of the setscrew and the face 20 of the slot. As is indicated in Fig. 3, the flattened face 20 will permit of a restricted rotation of the extremity 12, with consequent movement of the guard 8 from one side of the edge 7 to the other. This movement will be limited by the striking of the edge of the flattened face 20 upon the end of the setscrew 17. The setscrew 17 may be adjusted with reference to the flattened face 20 so that this relative movement will be just the correct amount to permit shaving with safety. This same movement will permit stropping of the razor.

When it is desired to clean the razor and its guard or to do any other thing which makes it desirable to remove the guard from the cutting edge of the blade, the extremities of the guard may be rotated in their respective sockets to the extent that member 16 will be sprung away from the flattened face 20, thereby permitting the face to pass over the end of the setscrew 17. As soon as this is done the guard may be freely moved entirely away from the cutting edge of the razor blade and when it is desired to have the guard re-assume operable position, it is swung back into position without changing the adjustments on the screw 17. In order to accomplish this movement it will be understood that member 16

must be so constructed as to have a slight resiliency.

When it is desired to again have the guard in operative position it is moved back to the position shown in Fig. 2 when the flattened portion 20, in cooperation with the end of the setscrew 17, will again function to normally prevent dislocation of the guard and permit of its efficient operation.

10 It will be obvious that various changes may be made in the arrangement, combination and construction of the various parts of my improved device without departing from the spirit of my invention and it is my intention 15 to cover by my claims such changes as may reasonably be included within the scope thereof.

What I claim is:

1. A razor having a blade portion, a guard 20 for the blade edge swingable over the edge on either side thereof thru an arc of approximately 180°, means normally restricting said swinging movement to position the guard slightly off center of the blade edge, on either 25 side thereof, and permitting the full swinging movement when abnormal pressure is applied thereto tending to swing it, said means being fixedly positioned longitudinally of the blade.

30 2. A razor having a blade portion, a guard for the blade edge swingable over the edge on either side thereof thru an arc of approximately 180°, means normally restricting said swinging movement to position the guard 35 slightly off center of the blade edge, on either side thereof, and permitting the full swinging movement when abnormal pressure is applied thereto tending to swing it, said means comprising a substantially flat spot on the 40 guard and a stop member cooperating therewith, one being movable, by the application of such pressure, with respect to the other.

45 3. A razor having a blade portion, a guard for the blade edge swingable over the edge on either side thereof thru an arc of approximately 180°, means normally restricting said swinging movement to position the guard slightly off center of the blade edge, on either 50 side thereof, and permitting the full swinging movement when abnormal pressure is applied thereto tending to swing it, said means comprising a substantially flat spot on the guard and a resiliently acting stop member cooperating therewith.

55 4. A razor including a blade member and a guard therefor, a portion of the guard being pivotally mounted to permit swinging of the guard in an arc of approximately 180°, said 60 pivoted portion having a relatively flat spot thereon and a stop member cooperating with said spot to normally limit rotation of said portion.

65 5. A razor including a blade member and a guard therefor, a portion of the guard being pivotally mounted to permit swinging of the

guard in an arc, said pivoted portion having a relatively flat spot thereon and a resiliently acting stop member cooperating with said spot to normally limit rotation of said portion and permit rotation past such limits when 70 required.

6. A razor having a blade provided with a cutting edge, a guard member having a portion adapted for swinging over the said edge in an arc of approximately 180° and a portion pivotally supported by the razor, said latter portion having a relatively flat spot thereon, said razor also carrying a stop member positioned adjacent the flat spot and adapted to cooperate therewith to normally limit the 80 pivotal motion of the pivoted portion.

7. A razor having a blade provided with a cutting edge, a guard member having a portion adapted for swinging over the said edge and a portion pivotally supported by the 85 razor, said latter portion having a relatively flat spot thereon, said razor having a resilient member carrying a stop member positioned adjacent the flat spot and adapted to cooperate therewith to normally limit the pivotal 90 motion of the pivoted portion.

8. A razor having a blade including an edge portion and a shank portion, a guard having a portion swingable over said edge, a member secured to the said shank having a recess receiving one end of the guard to form a pivotal mounting therefor, said guard end being provided with a relatively flat spot, and a second member secured over the pivoted end of the guard, carrying a stop member adapted to cooperate with said spot to normally limit the 95 pivotal action of said guard end.

9. A razor having a blade including an edge portion and a shank portion, a guard having a portion swingable over said edge, a member secured to the said shank having a recess receiving one end of the guard to form a pivotal mounting therefor, said guard end being provided with a relatively flat spot, and a second member secured over the pivoted end of the guard, carrying a stop member adapted to cooperate with said spot to normally limit the 100 pivotal action of said guard end, said second member comprising a resilient 105 piece.

HARRY A. KAUFMANN.
